William H. May Inventor

By Amester and Alvarie
Attorneys

UNITED STATES PATENT OFFICE.

WILLIAM H. MAY, OF ATLANTA, GEORGIA, ASSIGNOR TO LENA O. MAY, OF ATLANTA, GEORGIA.

PISTON.

Application filed September 9, 1922. Serial No. 587,070.

To all whom it may concern:

Be it known that I, WILLIAM H. MAY, a citizen of the United States, residing at Atlanta, in the county of Fulton and State of Georgia, have invented certain new and useful Improvements in Pistons, of which the following is a specification.

This invention relates to improvements in pistons.

10 The primary object of this invention is the provision of a piston of relatively simple construction, which embodies an improved cylinder lubricating arrangement.

15 A further object of this invention is the provision of a very durable piston which is so constructed that explosion pressures thereon are concentrated axially of the piston so that an explosive charge may be most effectively utilized.

20 A further object of this invention is the provision of an improved type of piston including upper and lower portions of exactly the same external diameter whose surfaces are adapted for sliding contact within an 25 engine cylinder, the improved piston embodying an oil pocket circumferentially intermediate the upper and lower portions thereof which has a cushioning effect upon the piston during reciprocatory movement 30 thereof, and thereby eliminate piston slap and irregular deteriorating movements thereof.

35 A further object of this invention is the provision of an improved piston of the above mentioned character which embodies an improved arrangement for feed of lubricant into an oil pocket provided circumferentially thereabout.

40 Other objects and advantages of this invention will be apparent during the course of the following detailed description.

45 In the accompanying drawing, forming a part of this specification, and wherein similar reference characters designate corresponding parts throughout the several views.

50 Figure 1 is a side elevation of the improved piston, showing the same as operatively used in the cylinder chamber of an internal combustion engine.

Figure 2 is a vertical cross sectional view taken through the improved piston.

Figure 3 is a transverse cross sectional view taken on the line 3—3 of Figure 2.

55 Figure 4 is an enlarged fragmentary sec-

tional view of an upper portion of the improved piston showing the cooperative construction of the details thereof.

In the drawing, wherein for the purpose of illustration is shown but the preferred embodiment of this invention, the letter A designates the improved piston pivotally mounted upon a connecting rod B, and adapted for slideable reciprocatory movement within the chamber 10 of a cylinder 11 of an internal combustion engine casing C.

Referring to the piston A, the same includes the cylindrical shaped casing 15, which may be formed of approved material, such as cast iron or aluminum. The casing 15 includes the cylindrical shaped top and bottom portions 16 and 17, whose exterior surfaces are exactly of the same diameter, so that the same are in sliding contact with the walls of the cylinder chamber 10 during movement of the piston A within the cylinder 11. The top wall 18 of the upper piston portion 16 is provided with a concaved surface 19, which may be struck from a radius of approximately twenty inches. 75 The concaved surface 19 intersects the outer circumferential surface of the upper portion 16 to provide a cylindrical acute edge 20 about the top of the piston casing 15. The relatively deep circumferential groove 23 is 80 provided annularly in the circumferential portion 16 of the casing 15 adapted to receive the piston ring 24 of any approved constructon.

The intermediate portion 25 of the casing 15 is provided with an outer surface 26 of less diameter than the outer surfaces of the upper and lower cylindrical portions 16 and 17 respectively. This portion 25 is disposed immediately below the piston ring groove 23, although an annular ring portion 28 is provided immediately below the groove 23, the outer circumferential surface of which is of slightly greater diameter than the diameter of the surface 26, although of less 100 diameter than the external diameter of the upper piston portion 16. Aligning wrist pin bearings 30 and 31 project interiorly of the intermediate portion 25, being a part thereof and which are adapted for receiving a horizontally disposed wrist pin 33 for attaching the connecting rod B to the piston casing 15 within the chamber 34 of said casing. A circumferential series of oil ducts or ports 35 are provided in the inter- 105

mediate portion 25, said ports 35 being of tapered formation and the larger diameter of said ports opening outwardly upon the surface 26 with the reduced ends of said ports opening into the chamber 34 of the casing 15 immediately below a horizontal annular shelf 38 which is provided by an annular projection 39 of the upper cylinder portion 16; said portion 39 having the piston ring groove 23 therein, as can readily be seen in Figure 2 of the drawings. It is to be noted that the lower marginal edge 40 provided by the ring shaped portion 28 diametrically intersects all of the oil ducts or ports 35.

The lower annular marginal edge of the cylinder portion 17 is provided with an inwardly bevelled surface 42, intersecting the exterior surface of the lower piston portion 17 to provide a circumferential sharp edge 43, said surface 42 converging upwardly inwardly of the chamber 34 of the piston casing 15.

In operation, the piston casing 15 is connected to the connecting rod B by means of a wrist pin 33, as can readily be understood, and is adapted for sliding in the chamber 10 of the cylinder 11. As the piston casing 15 reciprocates within the chamber 10, the lubricant upon the walls of the chamber 10 on the downstroke of the piston A will be scraped by the annular acute edge 43 so that said oil will be thrown upwardly over the bevelled surface 42 and directed into the chamber 34 provided in the piston casing 15. Due to the inclination of the surface 42, the lubricant will be forcibly thrown into the chamber 34 to engage the substantially horizontal shoulder 38, so that the lubricant is directed to the smaller ends of the oil ducts 35, and may exit into the chamber 50 which is provided intermediate the outer surface 26 of the piston portion 25 and the inner walls of the cylinder chamber 10, as can readily be seen from Figure 1 of the drawing. The oil entering this chamber 50 is effectively retained therein due to the fact that the outer circumferential surfaces of the piston upper and lower portions 16 and 17 are in snug engagement with the cylinder walls, so that the oil therein provides an effective cushion, the function of which is to lubricate the walls of the cylinder 11, and to buff any tendency of the piston to vibrate, thereby eliminating slap which is found in most types of pistons and materially lessens the efficiency of engine operation and results in shortening the life of the same. Referring to Figure 4 of the drawing, it can readily be seen that the outer surface of the portion 28 of the piston casing 15 is of less diameter than the outer surface of the upper piston portion 16, so that as the piston descends within the cylinder 10, an annular lower marginal edge surface 53 of the piston ring 24 extends outwardly from the surface of the piston portion 28 to scrape excessive lubricant from the side walls of the cylinder chamber 10, said lubricant being forced into the pocket 50. Should there be an excessive supply of lubricant within the chamber of pocket 50, the same will exit through the apertures 35 into the piston interior, 34 as can readily be understood. By the provision of the annular ring portion 28 upon the body of the piston A, the oil or lubricant is effectively regulated, so that the same cannot approach the piston ring 24 in excessive quantities, while at the same time, the flow of the lubricant into the pocket or chamber 50 is sufficient so that the same may be retained in quantities to perform the function for which the piston is provided. In addition, the annular ring portion 28 insures that excess oil within the pocket 50 may be directed through the ducts 35 into the piston interior 34.

From the foregoing description of this invention, it can be seen that the piston is provided with a top surface which will effectively regulate the pressure incident to an explosive charge so that strains will not unnecessarily occur upon the piston ring, but will be directed axially of the piston casing itself. The oil ducts 35 not only act as inlet but as outlet passageways, and are preferably drilled with a 60° taper. The oil pocket 50 is effectively filled with lubricant, at all times during engine operation.

Various changes in the shape, size and arrangement of parts may be made to the form of invention herein shown and described, without departing from the spirit of the invention or the scope of the claims.

I claim:

1. As an article of manufacture, a piston of the hollow casing type including an inner chamber, said piston having a circumferential series of tapered ducts communicating with the interior of said piston; and an annular shoulder extending within said piston casing immediately over said ducts, the piston casing having the lower edge thereof bevelled to upwardly converge axially of the piston and providing a sharp marginal edge about the lower end of the casing.

2. A piston comprising a body portion of the hollow type including cylindrical shaped upper and lower portions of exactly the same exterior diameter, said upper portion having the top surface thereof concaved and provided with an annular groove extending inwardly of the outer circumference thereof, said piston body including an intermediate portion having an exterior surface of reduced diameter with respect to the outer diameters of said upper and lower piston portions, said intermediate portion having a series of tapered ducts annularly pro-

vided in said intermediate portion immediately below the groove in said upper piston portion, said upper piston portion having a shoulder extending inwardly thereof immediately above said ducts, the lower piston portion having the lower marginal edges thereof acutely formed and provided with an upwardly converging surface adapted to receive oil or lubricant scraped from the cylinder wall for directing the same against the shoulder within said piston so that said oil may be directed through said ducts over the outer surface of the intermediate portion. 10

WILLIAM H. MAY.
